CLAIM

The ornamental design for a child chair, as shown and described.

DESCRIPTION

FIG. 1 is a perspective view of a child chair, showing our new design;

FIG. 2 is a front view of FIG. 1;

FIG. 3 is a rear view of FIG. 1;

FIG. 4 is a left side view of FIG. 1;

FIG. 5 is a right side view of FIG. 1;

FIG. 6 is a top view of FIG. 1;

FIG. 7 is a bottom view of FIG. 1; and,

FIG. 8 is a view showing the child chair shown in FIG. 1 in use.
The tray shown in broken lines viewed in FIG. 8 forms no part of the claimed design.
